109.

George Beaumont. Instrumental Co. Penn.

Pitter Patent.

The schedule referred to in this Pitter Patent, and making part of the same, containing a description of the mode of the invent. George Beaumont himself, of his improvement in the wedge-beater Threading Machine.

Be it known that George Beaumont of New Haven, Connecticut, a citizen of said County and State of Connecticut, have made an improvement in the machine for Threading Linen and Hitting, hereinafter called Beaumont's wedge-beater Threading machine which is described as follows, reference being had to the several drawings of this same machine as part of this specification. At. A. represents the frame. B. the high bar. C. the cap or cover which are made in the usual manner. The concave or the C. is made of two concavities, &c. - it is composed in the sides of the frame. The back or bottom of the concave is made in sections each containing one, two or more teeth of cast iron as represented at. D. and are riveted to the frame of the machine. The bottom of the concave may however be made of wrought iron as at. E. - with a shaft having a curved iron on which stands a wheel, through the concave and is made even by having a mill on the end of it. The concave may also be composed of alternate rows of these wrought and cast iron Beaters.

The cylinder F. is composed of two sections and is riveted, or riveted, & each supported by four arms having a wrought iron shaft. G. passing thro' the centre of this junction with turned pins uniting the suitable metallic pieces on the sides of the frame one end of the shaft passing beyond the side of the frame upon which is placed the discus, fulley, &c. - around these being placed the sleeves. H. which are bound together by two strong iron bands. I. - drawn over them ends. The beaters O. of the cylinder are made similar to those of the concave and are fastened in like manner. So thin as may be and in sections as represented at O. with a row of loops in each.

for a wrought iron bolt which passes through the same and through the sleeve and is secured by a nut on the inside. The section being also let into a concave slot in the face of the sleeve - two rows of beaters are arranged on each sleeve in such manner that they work between the plates of the concave without touching and being of a wedge like form. They may be brought nearer to or receded farther from each other by simply raising the side pieces of the frame which support the shaft of the cylinder. The beaters of the cylinder as well as those of the concave may be arranged in alternate rows of cast and wrought iron beaters as may be required. The machine is fed and operates in the usual manner. - All that I claim as my invention and desire to secure by Letters Patent consists in the peculiar formation of the beaters, as herein described.
